[57] CLAIM

The ornamental design for a bridging rainbow ornament for use primarily between a pair of audio components, substantially as shown and described.

DESCRIPTION

FIG. 1 is a front elevational view of the ornament resting atop spaced speaker enclosures;

FIG. 2 is a left side elevational view of the ornament of FIG. 1;

FIG. 3 is a right side elevational view of the ornament of FIG. 1;

FIG. 4 is a top plan view of the ornament of FIG. 1;

FIG. 5 is a rear elevational view of the ornament of FIG. 1; and

The speaker units shown by means of broken lines in

FIG. 1 are for illustrative purposes only.

FIG. 1

FIG. 2

FIG. 3

FIG. 4
